FIG. 1

FIG. 2

FIG. 3

FIG. 4

FIGURE 1 is a front perspective view showing the front and one side of a combined radio, phonograph and speaker unit showing my design, a movable panel at the front thereof being shown in its raised position,

FIGURE 2 is a front perspective view of a combined radio, phonograph and speaker unit of FIGURE 1 showing the other side and the front thereof with the said panel being in a lowered position, and

FIGURES 3 and 4 are top and side elevations respectively of a combined radio, phonograph and speaker unit of FIGURES 1 and 2.

The dominant features of my design reside in those portions shown in full line on the drawing.

The back of the cabinet is plain and unornamented.

I claim:

The ornamental design for a combined radio, phonograph and speaker unit, as shown and described.
